(57) **CLAIM**

The ornamental design for a washing machine, as shown and described.

DESCRIPTION

FIG. 1 is a perspective view of a washing machine, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is an enlarged view of portion 8 shown in FIG. 1;

FIG. 9 is an enlarged view of portion 9 shown in FIG. 1; and,

FIG. 10 is an exploded view of the washing machine shown in FIG. 1.

The broken lines in the figures illustrating portions of the washing machine are for environmental purposes only and form no part of the claimed design.

The dash-dot-dot broken lines encircling enlargement portions of the washing machine form no part of the claimed design.

1 Claim, 10 Drawing Sheets
